UNITED STATES PATENT OFFICE

2,495,445

DOUBLE PISTON VALVELESS PUMP OR
ENGINE

William F. Crenshaw, Lafayette, La.

Application January 12, 1946, Serial No. 640,936

1 Claim. (Cl. 103—163)

1

This invention relates to new and useful improvements in a double piston valveless pump or engine.

More specifically, the present invention proposes the construction of a device which may be used as a pump, compressor or motor, and which is characterized by having a cylinder, a piston therein, a piston in the first piston, the two pistons reciprocating at right angles to each other, and a drive shaft with an eccentric in the inner piston.

Still further, it is proposed to provide a device as aforesaid which is valveless.

Another object is to provide a device as aforesaid in which only one packed gland is needed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevation of a device constructed in accordance with this invention.

Fig. 2 is a side elevation looking from the right side of Fig. 1.

Fig. 3 is a plan view of Fig. 1.

Fig. 4 is a section on the line 4—4 of Fig. 3.

Fig. 5 is a section on the line 5—5 of Fig. 1.

Fig. 6 is a section taken substantially on the line 6—6 of Fig. 1.

The device of the present invention may act as a pump, compressor or motor (engine). Structurally, it has the same parts regardless of whether it drives its shaft by its piston or whether its piston is driven by its shaft. It will therefore be described in connection with its operation as a pump.

The pump, according to this invention, comprises a cylinder 10 having internal shoulders at its ends receiving heads 11 closing the opposite ends of the cylinder. The cylinder is shown vertically in the drawings and will be so described. A piston 12 is disposed in the cylinder for vertical reciprocation therein. The piston has a horizontal cylindrical bore 13 in which is disposed an inner piston 14. The inner piston has a horizontal cylindrical bore 15 at right angles to the bore 13.

The shaft 16 of the pump is disposed horizontally and extends through an orifice 17 in the side wall of the outer cylinder 10 and through the bore 15 of the inner piston 14 to the opposite side of the cylinder 10 where it is journalled in

5 a recess 18 in the inner face of the cylinder 10. This shaft 16 has an integral cylindrical eccentric 19. When the shaft 16 is rotated and the eccentric is rotated it moves the inner piston 14 back and forth in the large piston 12 and at the same time moves the large piston 12 up and down in the cylinder 10.

10 The shaft 16 is packed in the orifice 17 by a gland 20 which may be of any well known construction, the gland 20 and the cylinder heads 11 tightly sealing the cylinder 10 against loss of lubricant or other fluids. This necessity of but a single gland adapts the device of the present invention for such uses as a sealed unit in a refrigerator.

15 The device is, as aforesaid, valveless. The cylinder is provided with an inlet port 21 and by a diametrically opposite outlet port 22, these ports being in the side wall of the cylinder 10. 20 The various parts of the device are interconnected for fluid flow by an intricate system of ports which are as follows:

25 There is a port 23 in the top of the outer piston 12 communicating with a smaller port 24 in the top of the inner piston 14, port 24 communicating with the interior of the smaller piston. There is a port 25 in the side of the inner piston 14 also communicating with the interior thereof; and with a passage 26 in the eccentric 19. There is another port 27 in the other side wall of the inner piston 14 and this, like the port 25, communicates with a passage 28 in the eccentric 19. Passages 26 and 28 communicate respectively with ports 29 and 30, also in the eccentric. Finally there is a port 31 in the inner piston 14 opposite port 24.

35 The operation of the pump is as follows:

30 Power is applied to the shaft 16. The eccentric 19 is rotated as the shaft rotates and moves the inner piston 14 back and forth and the large piston 12 up and down. Shaft 16 rotates clockwise, and port 21 takes in fluid to be pumped while port 22 acts as the outlet. When the large piston 12 is at dead center, the inner piston 14 is at mid-stroke and vice versa.

45 The outer piston 12 has a sliding movement in the cylinder 10, moving from one end of the cylinder to the other end, due to the eccentric 19, which causes the inner piston 14 to slide from one end of the outer piston 12 to the other end thereof, or nearly so. The eccentric 19 on the shaft 16 thus produces reciprocation of the outer piston 12 in the cylinder 10, from end to end, and reciprocation of the inner piston within the tubular outer piston.

50 The movement of the outer tubular piston in

the cylinder 10 generates a suction impulse at one end of the outer piston, and a compression impulse at the other end. The movement of the inner piston in the tubular outer piston also generates a suction impulse at one end of the inner piston and a compression impulse at the other end.

When the two pistons are in the position shown in Fig. 4, the inner piston will be moving to the left and the outer piston will move upwardly. Fluid will then be drawn through the intake port 21 to the chamber 13. As the eccentric 19 turns in the bore of the inner piston, it will uncover the port or passage 31 as it forces the outer piston 12 upwardly, and fluid will be forced through the passage 31 to the space between the lower end of the outer piston 12 and the cylinder 10. As the eccentric continues its rotation, the passages 27 and 28 will be placed in communication with each other and the fluid will be discharged above the outer piston, and thence discharged through the port 22 to any service connection coupled to this port.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described by invention, what I claim as new, and desire to secure by United States Letters Patent is:

An apparatus of the class described, comprising a one-piece cylinder having end walls closing the ends thereof and diametrically opposite inlet and outlet ports midway of the ends thereof, an outer piston slidable within said cylinder parallel to the longitudinal axis of said cylinder and formed with a bore extending at right angles to the longitudinal axis of said cylinder, an inner piston slidable within the bore of said outer piston and formed with a bore extending at right angles

to the bore of said outer piston, said outer piston being formed at its ends with ports concentric with the longitudinal axis of said cylinder and in communication with complementary ports in the adjacent sides of said inner piston, said inner piston being formed at its ends with ports concentric with the axis of said bore of said outer piston, said inlet and outlet ports being in communication with the bore of said inner piston through openings formed in the sides of said outer piston at right angles to its bore, a shaft rotatively extended through one side wall of said cylinder midway of its ends, through said openings of said outer piston, through the bore of said inner piston and having its inner end rotatively supported within a recess formed in the inner face of the diametrically opposite wall of said cylinder, a cylindrical eccentric formed on said shaft within the bore of said inner piston for reciprocating said inner piston within the bore of said outer piston and for reciprocating said outer piston within said cylinder when said shaft is rotated, diametrically opposite ports formed in said eccentric for successively communicating with said side ports and said end ports of said inner piston as the eccentric rotates within said inner piston, and ports extending in opposite directions from the ports of said eccentric and extended through the opposite ends of said eccentric and communicating with the bore of said inner piston.

WILLIAM F. CRENSHAW.
